CLAIM

The ornamental design for a handbag with interchangeable handbag cover, as shown and described.

DESCRIPTION

FIG. 1 is a front perspective view of a handbag with attached, interchangeable handbag cover, with the opposing rear view being a mirror image thereof;

FIG. 2 is a front perspective view thereof showing the handbag cover in a partially opened position with respect to the base handbag;

FIG. 3 is a front elevational view of the base handbag, and handbag cover shown in FIG. 1 with the opposing rear view being a mirror image thereof;

FIG. 4 is a top plan view thereof;

FIG. 5 is an elevated left view thereof, with the opposing right view being a mirror image thereof; and,

FIG. 6 is an elevated bottom view thereof.

The claimed design is shown broken away to illustrate indeterminate length.
